UNITED STATES PATENT OFFICE.

SAMUEL KATZ, OF GREENVILLE, SOUTH CAROLINA.

CHANGEABLE SIGN OR ADVERTISING DEVICE.

Application filed July 29, 1924. Serial No. 728,955.

The object of my said invention is the provision of a changeable sign or advertising device adapted to display placards or panels in succession and in such manner that each placard or panel is exhibited at one time and is retained in exposed position for a predetermined period of time so as to enable observers to appreciate its import.

Other objects and practical advantages of the invention will be fully understood from the following description and claims when the same are read in connection with the drawings, accompanying and forming part of this specification, in which:—

15 Figure 1 is an elevation of the sign or display device constituting the preferred embodiment of my invention.

Figure 2 is a horizontal section taken in the plane indicated by the line 2—2 of Figure 1.

Figure 3 is an enlarged vertical section taken in the plane indicated by the line 3—3 of Figure 2.

Figure 4 is a detail section taken on the line 4—4 of Figure 3 and illustrating my novel mechanism for imparting a step by step movement to the rotor of my novel device.

Figure 5 is a detail horizontal view of a portion of the said mechanism.

Figure 6 is a side elevation of a portion of said mechanism.

Figure 7 is a view illustrative of the bearing in which the rotor shaft is stepped.

35 Figure 8 is a detail vertical section of the rotor.

Figure 9 is a horizontal section of a modified rotor hereinafter explicitly referred to.

Similar numerals of reference designate 40 corresponding parts in all of the views of the drawings.

Among other elements my novel sign or display device comprises a casing body which is preferably formed of sections 1 and 2, hingedly connected at 3 and adapted to be secured in closed position at 4. One section 2 of the casing body is provided with a display opening 5 preferably glazed at 6, and over the said display opening is arranged a reflector 7 in which may be arranged an incandescent electric lamp or any other appropriate lamp, the said lamp being designed to illuminate the placards or panels of the rotor as each placard or panel is positioned in coincidence with the opening 5.

Appropriately supported in the casing of the device is a base 8 on which is fixed a substantially U-shaped upright frame 9. Also carried by the base 8 is an electric motor 10 with a worm 11 on its armature shaft 12, the said worm 11 being meshed with a worm gear 13 on a shaft 14 that is carried by an auxiliary upright frame 15, said frame 15 also affording bearings for the armature shaft 12.

Journaled in the first-named upright frame 9 is a shaft 16 which is stepped at 17 in a bearing 18.

Mounted on and rotatable with the shaft 16 is a rotor, Figures 2 and 3, the said rotor including a base 20 and a body 21 fixed on said base 20 and having by preference eight sides each of which is about the same area as the display opening 5. Manifestly the body 21 of the rotor may have any desired number of sides without affecting my invention, each of the said sides being adapted to carry a panel or placard 22 of advertising character. As clearly shown in Figures 2 and 3, the base or platform 20 of the rotor is larger than the body 21 and projects from the lower portion of the said body, and is adapted to carry stems 23, one in front of each of the several sides of the body 21. The said stems 23 which may be of any appropriate construction are adapted to support and display articles of various kinds in such manner that each of the articles is for a time displayed through the opening 5 as appears in Figure 1.

Appropriately fixed to the upright shaft 16 is a gear 30, Figures 3, 5 and 6. The said gear 30 is disposed horizontally and is provided with teeth 31 inclined from the vertical and beveled at opposite sides as designated by 32 and 33, respectively. For co-operation with the said gear 30 a disk 34 is fixed to the worm gear 13, the said disk 34 having a lateral curvilinear cam portion 35 cut therefrom adjacent to its periphery as best shown in Figures 3, 4 and 6. In virtue of this construction it will be manifest that when the electric motor is in operation and the disk 34 is rotated, the cam portion 35 of the disk 34 will pass, incident to each rotation of the disk 34, through one of the interdental spaces of the gear 30. In passing through the said interdental space of the gear 30 the cam portion 35 will operate to turn the display rotor through one-eighth

of a revolution, the parts being so relatively arranged that when the rotor is turned in the manner described one of its placards will be positioned opposite or in coincidence 5 with the display opening 5. Manifestly the disk 34 is rotated at a low rate of speed and from this it follows that after cooperating with the gear 30 and turning the rotor through a part of revolution, the cam portion 10 35 on the disk 34 will pass out of engagement with the gear 30 and will permit the rotor to dwell with one of its placards or panels displayed so as to enable observers of the device to fully appreciate the import 15 of the displayed panel or placard before the cam portion 35 again engages the gear 30 for movement of the rotor.

It will be apparent from the foregoing that my novel sign or display device is calculated to attract attention when placed in a show window or at any other desired point; also, that the step by step movement of the rotor is advantageous inasmuch as it allows ample time for each panel and the stand in front of the same to make display to advantage before the rotor is again moved for the display of another panel and an article on the stand in front of the said panel.

I have specifically described the preferred embodiment of my invention in detail in order to impart an exact understanding of the same. I do not desire, however, to be understood as confining myself to the specific 25 construction and relative arrangement of parts as disclosed inasmuch as the scope of my invention is defined by my appended claims and within said claims changes or modifications may be made without affecting 40 my invention.

For instance in lieu of the rotor shown in

Figures 2, 3 and 8 it is within the purview of my invention to employ the rotor shown in Figure 9, the said rotor lacking a projecting platform but having stems 23* on its lower wall 20* together with sides in the form of panels or placards 22* in front of the vertical centers of which the stems 23* are disposed.

Having described my invention, what I claim and desire to secure by Letters-Patent, is:—

1. A sign or display device comprising a casing having a display portion, a rotor disposed in the casing and having a plurality of sides arranged to be positioned successively in co-incidence with the said display portion of the casing, a substantially U-shaped upright frame in said casing, a shaft carrying the said rotor and arranged in bearings formed in the arms of the upright frame, a gear having teeth formed at an angle to the plane of rotation of the gear and secured to said shaft, a disk mounted for rotation, a lateral curvilinear cam portion cut from said disk and arranged to pass through the interdental spaces of the said gear and turn the rotor step by step and permit said rotor to dwell with its sides in co-incidence with the display portion of the casing, a worm gear having secured thereto the said disk and motor arranged in the casing and having a worm meshed with said worm gear.

2. A rotor comprising a multi-side body with the sides exteriorly of horizontal concave cross-section, a bottom wall, and article-holding stems rising from said wall in front of said sides.

In testimony whereof I affix my signature.

SAMUEL KATZ.
